(57) **CLAIM**

The ornamental design for a pistol grip for a firearm, as shown and described.

DESCRIPTION

FIG. 1 is a first perspective view of the pistol grip for a firearm according to the present design;

FIG. 2 is a second rotated perspective view of the design of FIG. 1;

FIG. 3 is a front plan view of the design of FIG. 1;

FIG. 4 is a rear plan view of the design of FIG. 1;

FIG. 5 is a right side view of the design of FIG. 1;

FIG. 6 is a left side view of the design of FIG. 1;

FIG. 7 is top view of the design of FIG. 1; and,

FIG. 8 is a bottom view of the design of FIG. 1.

1 Claim, 5 Drawing Sheets
